ATTORNEY

UNITED STATES PATENT OFFICE.

JOHN F. GERAGHTY, OF NEW YORK, N. Y., ASSIGNOR TO WILLIAM R. NOE, OF EAST ORANGE, NEW JERSEY.

DESIGN FOR A WALL-LAMP HOLDER.

No. 37,947.

Specification for Design.

Patented April 10, 1906.

Application filed December 4, 1905. Serial No. 290,314. Term of patent 7 years.

To all whom it may concern:

Be it known that I, JOHN F. GERAGHTY, a citizen of the United States, residing in the city of New York, borough of Brooklyn, in the county of Kings and State of New York, have invented a new, original, and ornamental Design for Wall-Lamp Holders, of which the following is a specification, reference being had to the accompanying drawing, forming part thereof and showing a perspective view of a wall-lamp holder according to my new design.

I claim—

The ornamental design for a wall-lamp holder as shown.

JOHN F. GERAGHTY.
